UNITED STATES PATENT OFFICE.

GEORGE M. BROWN, OF CAMBRIDGE, MASSACHUSETTS.

CARBURETER.

1,151,159.

Specification of Letters Patent. Patented Aug. 24, 1915.

Application filed October 3, 1913. Serial No. 793,250.

To all whom it may concern:

Be it known that I, GEORGE M. BROWN, a citizen of the United States, and resident of Cambridge, in the county of Middlesex and State of Massachusetts, have invented new and useful Improvements in Carbureters, of which the following is a specification.

This invention relates to carbureters, and its object is to provide a simple and efficient carbureter for use in conjunction with internal combustion engines.

My improved carbureter is so constructed that when once properly adjusted it requires no regulation of the liquid fuel or of the air entering the mixing chamber, and that a thorough and complete mixing of the fuel and air, and an even and powerful quality of explosive mixture, will be produced, without waste of the fuel, irrespective of the speed of the engine.

The invention consists in a group of functionally related factors of which the co-operative performance insures a practically perfect gaseous mixture of air and vaporized volatile fuel and automatically regulates the proportion of air and fuel to suit varying conditions imposed by the engine which is supplied by the carbureter, and by external conditions of temperature and humidity of the surrounding air.

The cardinal factor which characterizes my invention in its more generic aspect is a centrifugal separator, which co-operates functionally with the air supply, volatile liquid fuel supply, and air-and-fuel mixture duct. The primary function which the centrifugal separator performs in this environment is the separation from the gaseous content of the carbureter of that portion of volatile fuel which persists in liquid form, so that only completely volatilized fuel is allowed to pass to the engine in mixture with air. A secondary, but none the less quite important, function, performed by the centrifugal separator in what I conceive to be the best example of my invention, is supplying compensatory fuel vapor by evaporation of liquid volatile fuel from the surfaces of the separator, an evaporation which automatically maintains a proper fuel-proportion in the combustible mixture supplied to the engine, and automatically adjusts the inspirative draft upon the liquid fuel supply duct. A secondary factor, contributing to the characteristics of my invention in its more specific aspects, is an in-draft air regu-

lator which, operating in conjunction with the usual throttle valve in the mixture duct leading to the engine, adjusts the pressure in the mixing chamber of the carbureter to variations in degree of throttle opening, thus graduating the pressure under which the centrifugal separator operates.

In the accompanying drawing which illustrates in vertical section a carbureter embodying the invention in one form, A represents a mixing chamber, of metal, glass or other suitable material, which is preferably substantially spherical in form, and may be made in two sections screwed together as shown.

A fuel nozzle B, made with a restricted delivery passage enters through the bottom of the mixing chamber A, and is screwed or otherwise secured in place in the wall of the chamber. Opposite the nozzle B is a deflector plate b, or other suitable form of atomizing device to break up into small particles or form into spray, the jet of fuel issuing through nozzle B. It will be understood that the fuel may be gasoline, kerosene, ether or other volatile fluid, for which the engine to be supplied by the carbureter is adapted. The atomizing device b may be supported in the mixing chamber by legs b'. In order to regulate the flow of the fluid and the influence of the suction to which it is subjected the nozzle B is made adjustable in the wall of the chamber A, so that it may be projected a greater or less distance into the chamber. The lifting force of the vacuum within the chamber will be found stronger near the center of the chamber than near the periphery. Thus the velocity of the fluid and consequently the consumption of the fuel and its relation to the demands of the engine and the volume of the air may be varied.

C represents an air inlet tube or pipe, entering the mixing chamber A through the top, and curved or bent as shown, so that its mouth will face away from the center of the mixing chamber and toward the wall.

D is an outlet pipe for the explosive mixture leading to the engine, and also enters through the top of the mixing chamber, and is similarly curved or bent, but in the opposite direction, so that its mouth will face away from the center of the chamber toward the wall opposite to that faced by the mouth of pipe C. It will be understood that the pipes C and D need not necessarily enter the

mixing chamber through the top, though in practice I believe that to be the best location.

The gas outlet pipe D is provided with a throttle valve E; and the air inlet pipe C has a shutter F, partially closing the pipe, and operated in unison with the throttle valve E by means of the link connection G, so that when the throttle E is opened or closed more or less, the shutter F will also 10 open or close more or less.

The fuel nozzle B communicates with the vessel H, which may be supplied with the gasolene or other fuel from a tank in the usual manner, through pipe h, and is secured 15 directly to the under side of the mixing chamber A. The pipe h in supplying the vessel H is controlled by a ball valve h' connected to a float J, herein shown as annular in form and surrounding the nozzle B. As 20 the fluid fuel is withdrawn from vessel H through nozzle B, the float J will fall, open the valve h' and admit more fuel through pipe h.

The valves E and F being opened, more or 25 less according to controlling external conditions, and the engine supplied by the carbureter being in operation, a strong in-draft is set up in the carbureter. Air entering at the duct C impinges obliquely against the 30 curved inner wall of the chamber A and whirls centrifugally, passing by the nozzle of the volatile fuel duct B and inspirating volatile fuel, which is atomized or sprayed as it issues from the duct B. The centrifugal motion 35 of the current of air throws the particles of fuel which persist in liquid form outwardly against the walls of the chamber A; larger particles of liquid are thrown to the circumference of the rotating stream more 40 readily than smaller particles, so that the liquid globules, which by reason of their size are best qualified to delay complete evaporation, are with the greatest certainty deposited on the inner surface of the chamber A, there 45 to spread as a thin film in close adhesive contact with the solid material of which the chamber A is composed. While all of the air and vaporized fuel passes eventually into the mixture duct D, a considerable proportion 50 of the mixture at any given moment in the chamber A whirls repeatedly around, making the centrifugal vortex complete. The chamber A thus performs the function of an air and fuel mixing chamber, and also that 55 of a centrifugal separator. The gas-pressure in this separator chamber is least at the center and greatest near the circumference, by reason of the centrifugal action. Therefore, if the nozzle of the liquid fuel duct B is ad- 60 justed to a position near the center of the centrifugal vortex, the vacuum-draft on the liquid will be by so much increased. This will, of course, be offset by the increased vertical distance through which the fuel has to 65 be drawn from the float-chamber if the lat-

ter remains at the same position. I prefer, however, to locate the nozzle of the fuel inlet duct B at a point in the whirling body of air near to the surface of the chamber A, so that liquid fuel, as distinguished from vaporized 70 fuel, may be the more readily deposited on the surface of the chamber A. Moreover, in order that liquid spray may not penetrate too far into the chamber A, I provide the baffle plate b, which assists also in breaking 75 up the liquid spray and furnishes some evaporating surface in supplement to the walls of the chamber A.

Besides mechanically removing liquid particles from the air stream by depositing them 80 through centrifugal separative action on the walls of the chamber A, the separator-mixer performs the function of supplying a continuously replenished film of volatile liquid to the walls of the chamber, and this film 85 continually evaporates, enriching the combustible mixture with truly gaseous fuel. Thus the carbureter acts as a combined spray and surface carbureter, contributing the values of each type, without involving 90 the characteristic defects of either.

The vacuum draft on the liquid supply duct is automatically qualified and regulated by the evaporation of liquid fuel deposited on the chamber walls. If a sudden increased 95 demand for combustible mixture is made on the carbureter, the film of liquid fuel on the chamber walls responds by more rapid evaporation due to lowered pressure and increased velocity of flow of air in the chamber, checking what otherwise might be an unduly violent influx of liquid fuel into the chamber, since increased rate of evaporation will tend to raise the vapor pressure in the chamber.

When the engine is throttled by partial 105 closure of the valve E, the valve F also increases its constrictive effect on the air duct C. This produces a lowering of pressure in the chamber A, to a degree greater than would be the case if valve F alone operated 110 to vary the effective cross section of the passages, and therefore the lowered pressure in the chamber A compensates for the lower velocity of flow, thus insuring a full delivery 115 of liquid from the duct B at a time when a richer combustible mixture is likely to be demanded.

Such are the automatic regulating and compensating faculties of my improved carbureter that I have found it entirely feasible 120 to dispense with a needle valve or any other adjuster of the liquid fuel duct, and with a supplemental air supply passage and its usual accompaniment of valve and spring. With the simplicity of construction, absence 125 of springs, mechanical adjustments, and moving parts, which characterize the above described carbureter, all the automatic adjustability to varying conditions (heretofore possessed only by the more complicated va- 130

rieties of carburetors) which is required in modern internal combustion engine practice, is obtained.

I believe the most important characteristic of my improved carburetor to be the separation of persistently liquid fuel particles from the stream which enters the engine manifold or supply duct. The other characteristics above described, follow as 10 incidents to this main characteristic.

The shape and proportions of the centrifugal separator chamber may, of course, be widely varied, to suit the notions of the designers or the requirements of particular 15 engines, but the characteristic utility of my invention will be served in any carburetor in which the liquid fuel particles which might otherwise be drawn into the engine, are centrifugally separated from the mixture and 20 deposited upon surfaces from which the liquid may evaporate according to the fluctuating demand.

The spherical form of gas mixing and liquid separating chamber, shown and described herein, has proved effective in practice, and the sphere is therefore believed to be the preferable form of this characteristic member of my improved carburetor. Plenty of space is afforded on either side of the 30 direct path between the ducts C and D, to allow the gaseous contents of the chamber A to stir about and mix thoroughly, while the vertical or eddying motion always facilitates the separation from the gases of liquid 35 particles so long as those persist.

The location of the fuel float-chamber immediately below the delivery nozzle B is important, because the effective level, or head, of the liquid fuel, is not affected by 40 changes in the inclination of the carburetor to the horizontal normal position, changes which take place constantly when a motor is traveling on the road. Since no mechanical regulation is necessary or desirable in 45 this improved carburetor, the liquid fuel inlet is not so constricted as in carburetors heretofore in general use, and any change of relative level between the liquid in the float chamber and the delivery opening of the 50 liquid-duct B will affect my improved carburetor more than a similar change will af-

fect the behavior of carburetors of the present standard forms.

While I believe that a substantially spherical form is the best for the mixing chamber, 55 my invention is not restricted to that particular form. Good results may be obtained if instead of being spherical, the lower part of the chamber only is hemispherical, while the upper part might be of other form. Indeed 60 many of the advantages of my invention might be realized with a mixing chamber of other than spherical or hemispherical forms, the important characteristics being that the chamber should be large relatively to the 65 passages; and that the flow of the air therethrough should be in tortuous currents and eddies.

It will be observed that with this invention no needle valves, and no springs are 70 required. The inflow of air, and the speed of the fluid jet are automatically responsive to and regulated by the degree of vacuum, or tension produced by the engine and controlled by the throttle E. 75

I claim:

1. In a carburetor, the combination of a spherical mixing chamber, a liquid fuel duct entering said chamber at one side, and an air inlet duct and a mixture delivery duct 80 each extending into the spherical chamber and presenting their respective openings to the side thereof, one on one side and the other on the other side of the fuel inlet duct.

2. In a carburetor, the combination of a spherical mixing chamber, a liquid fuel duct entering said chamber at one side, and an air inlet duct and a mixture delivery duct each extending into the spherical chamber and presenting their respective openings to 90 the side thereof, one on one side and the other on the other side of the fuel inlet duct, and throttling valves, one in the mixture duct and the other in the air inlet duct, the two valves connected to move in unison. 95

Signed by me at Boston, Massachusetts, this 16th day of September, 1913.

GEORGE M. BROWN.
